(57) **CLAIM**

The ornamental design for a head assembly for refrigerator filter as shown and described.

DESCRIPTION

FIG. 1 is a top front perspective view of a head assembly for refrigerator filter showing my new design;

FIG. 2 is a bottom front perspective view thereof;

FIG. 3 is a front elevation view thereof;

FIG. 4 is a rear elevation view thereof;

FIG. 5 is a left-side elevation view thereof;

FIG. 6 is a right-side elevation view thereof;

FIG. 7 is a top plan view thereof;

FIG. 8 is a bottom plan view thereof;

FIG. 9 is an enlarged view of portion 9 in FIG. 2;

FIG. 10 is a cross-sectional view taken along line 10-10 of FIG. 3;

FIG. 11 is a top front perspective view, shown in an environment of use; and,

FIG. 12 is an enlarged view of portion 12 in FIG. 11.

The broken lines shown in FIGS. 1 to 10 depict portions of the head assembly for refrigerator filter and form no part of the claimed design. All other broken lines shown in FIGS. 11 and 12 depict environment and form no part of the claimed design. The dot-dash lines defining the boundaries of the claimed design form no part thereof.
